MESSAGE HOLDER

Caspar J. Korndorfer, Allendale, N. J., and Leslie T. Hand, Brooklyn, N. Y., assignors to Morsegraph, Inc., New York, N. Y., a corporation of New York

Application May 9, 1936, Serial No. 78,930

1 Claim. (Cl. 24—252)

This invention relates to standing holders for sheets of paper in the form of telegrams and other notices placed there by the operators of typewriting and recording instruments, or by messengers, and intended for quick placement and removal.

In places of business having numbers of recording instruments and operators therefor it is desirable that each operator have beside him one or more of these standing holders, and also it is desirable that each receiving holder shall be provided with visible indicating means as a guide to messengers carrying sheets with written communications to be transmitted to other cities, so that a messenger may know at a glance which holder is to receive the message.

Other features and advantages of our invention will hereinafter appear.

In the drawing:

Figure 1 is a front elevation of a standing holder provided with tensional gripping means, support engaging means, and with indicating means.

Fig. 2 is a side elevation thereof.

Fig. 3 is a front elevation of a duplex holder having modified support engaging means.

Fig. 4 is a detail view showing still another form of support engaging means, and

Fig. 5 is a detail view of a foot stand for a holder.

In Figures 1 and 2 we have shown the holder as comprising a pole or shaft 1 which is extended vertically from a base element 2 which with the removable keeper 3 is rectangular in form and adapted to fit upon a rail (not shown), to thus constitute pole supporting means.

Secured to the pole 1 is a U-shaped bracket 4 in which is pivoted, at 5, a lever arm 6, whose longer portion from the pivot extends downwardly along the pole and has an inward bend, at 7, that lies against said pole, and an outturned terminal portion 8.

The shorter portion of arm 6 from the pivot 5 extends upwardly within the bracket 4, and a thumb-screw 9, threaded through the upper end 45 of arm 6, contacts one end of a helical spring 10 that lies between said screw and the pole. The spring 10 applies tension to arm 6, above pivot 5, to thus press the bend 7 of said arm against the pole, the thumb-screw serving to regulate the degree of tension employed, and a lock nut 11 is provided to retain the thumb-screw in its adjusted position.

It will be appreciated that the degree of tension with which arm 6 bears against the pole is slight and not more than sufficient to enable the bend

1 to frictionally sustain one or more paper sheets that are slipped between said bend and pole, and so that the sheets may be withdrawn with as much ease as they have been slipped into the frictional engagement referred to.

It is to be understood that the operator, having typed a message on a sheet of paper, will at once place it in the holder where it will be handily disposed for quick removal by a passing messenger.

The indicating means for the holder to apprise the messenger as to which operator is to receive a message he is conveying comprises a plate or board in the form of a panel 12 having spaced channels 13 on its face adapted for the reception of cards 14 which may each bear an indication 15 symbolizing the name of a city, denoting to the messenger that messages to a city represented by the displayed symbol are to be placed in the holder carrying that symbol. In Fig. 1 we have placed the symbol SY on one of these cards as 20 illustrating the purpose referred to, this symbol representing, for example, the name of the city Syracuse.

In Fig. 3 we have shown the U-shaped, double message holder, it having the poles 15, 16 with 25 tensional message holding arms 6, and with connecting bail 17 to which a boss 18 is attached. A screw 19 is extended from boss 18 and may be passed through a table 20 and secured thereto by a wing nut 21.

Other forms of base support for the holder are shown in Figs. 4 and 5. Thus in Fig. 4 clamping jaws 22, 23 are mounted on pole 1, the jaw 22 being fixed and the jaw 23 operable by a wing nut 24 for the purpose of clamping a table 25 between said jaws.

In Fig. 5 the pole 1 is shown as supported by a pedestal 26.

Variations within the spirit and scope of our invention are equally comprehended by the foregoing disclosure.

We claim:—

In a device of the character described, a support, a U-shaped bracket attached to said support, the top rear portion thereof being cutaway 45 to partially embrace said support, a non-flexible arm extended along said support, said arm having an inturned bend for contact with said support and an outturned terminal portion continued from said bend, pivotal means connecting said 50 arm and bracket, said means being disposed at the lower front portion of the legs of said U-shaped bracket, whereby that portion of said arm above said pivotal means has its front section arranged substantially in the same plane with the 55

front face of each of the legs of said bracket, a thumbscrew threadedly engaging the upper end of said arm, a spring inclosed within the confines of said U-shaped bracket and positioned adjacent the bight portion thereof, said spring extending between said support and the inner end of said

thumbscrew to tension the contact of said in-turned bend of said arm with said support and means borne by said thumbscrew to hold said spring in an adjusted tensioned position.
